REVERSIBLE MINING MACHINE CHAIN

Charles L. Bowman, Canton, Ohio, assignor to
 The Bowdil Company, Canton, Ohio, a corpora-
 tion of Ohio

Application December 12, 1936, Serial No. 115,491

10 Claims. (Cl. 262—33)

My invention relates in general to mining ma-
 chine cutting chains, and more particularly to
 reversible mining machine cutting chains.

An object of my invention is the provision of a
 5 reversible mining machine chain adapted to hold
 cutting bits in either one of two positions, so that
 the chain may be operated in either the forward
 or reverse direction to cut the coal or other
 material.

10 Another object of my invention is the provision
 of a reversible mining machine chain lug hav-
 ing two opposed recesses for holding the cutting
 bit whereby the chain may be operated either in
 the forward or reverse direction by positioning
 15 the cutting bit in either one of the two opposed
 recesses.

Another object of my invention is the provision
 of a reversible mining machine chain lug having
 two opposed recesses, wherein either one of the
 20 two recesses is adapted to alternately receive a
 cutting bit or a plug so that the set screws, which
 hold either the cutting bit or the plug may be
 tightly turned in so as to prevent them from be-
 25 coming lost when the mining machine chain is
 in operation.

Another object of my invention is the pro-
 vision of preventing the coal dust or other mate-
 rial from collecting in the recesses of the chain
 lug which hold the cutting bit or the plug, which
 30 if allowed to collect, would interfere with the in-
 sertion of the cutting bit or plug.

Another object of my invention is the provision
 of a reversible mining machine chain lug adapted
 to hold a rhomboidal shaped bit, wherein the
 35 chain lug has two opposed recesses for respec-
 tively receiving the bits for forward or reverse
 cutting, each of said recesses having an abut-
 ting surface against which the rear face of the bit
 abuts, the abutting surfaces sloping downwardly
 40 and inwardly to form a common bottom for both
 recesses and to form a substantially large lug por-
 tion between, and to give strength to, the two
 abutting surfaces, with a minimum of longitudi-
 45 nal distance between the cutting points of the
 bit and a line passing vertically through the
 center of the lug.

Another object of my invention is the pro-
 vision of a reversible mining machine chain lug
 having opposed recesses for respectively receiv-
 50 ing the bits for forward and reverse cutting,
 wherein the longitudinal distance between the
 cutting point of the bit and a vertical line pass-
 ing through the center of the lug is reduced to a
 minimum.

55 Another object of my invention is the pro-

vision of a reversible mining machine chain lug
 having two opposed recesses for respectively re-
 ceiving the bits for forward or reverse cutting,
 wherein the central lug portion between the op-
 posed recesses constitutes the uppermost part 5
 of the lug, and wherein the end portion upon each
 side of the recesses slopes downwardly from the
 central lug portion to reduce the radial distance
 between the pivotal turning point of the lug when
 going around the end of the cutter bar and each 10
 of the upper end corners of the lug.

Another object of my invention is the pro-
 vision of a double and reversible mining machine
 chain lug having two sets of opposed recesses for
 respectively receiving a set of bits for forward 15
 and reserve cutting, one of said sets of opposed
 recesses being positioned upon one side of the
 longitudinal and vertical center of the chain lug
 and the other set of opposed recesses being posi-
 20 tioned upon the other side of the said longitudinal
 and vertical center of the chain lug.

Another object of my invention is the pro-
 vision of having one of said sets of opposed re-
 cesses positioned farther from the said longitu-
 25 dinal and vertical center of the chain lug than
 the other of said sets of opposed recesses.

Another object of my invention is the provision
 of opposed surfaces in the bottom of the bit re-
 cesses, to prevent the bit from tipping forward
 upon being inserted, which forward position 30
 would allow the bit to drop too far into the re-
 cesses and not keep the proper gauge, thus caus-
 ing difficulty when the set screw is tightened.

Another object of my invention is the pro-
 vision of a mining machine chain adapted to hold 35
 a cutting bit and made up of a plurality of sec-
 tions, each section comprising three designs of
 chain lugs arranged in four positions and adapt-
 ed to hold six cutting bits.

Another object of my invention is the provision 40
 of a reversible mining machine chain lug adapted
 to hold cutting bits for forward and reverse cut-
 ting respectively and made up of a plurality of
 sections connected reversely to each other, each
 section comprising three designs of chain lugs ar- 45
 ranged in four positions and adapted to hold six
 cutting bits, each of said lugs having opposed
 recesses for receiving the bits for forward and
 reverse cutting respectively.

Another object of my invention is the provision 50
 of a reversible double-ended cutting bit of rhom-
 boidal shape in side elevation and having two sub-
 stantially parallel diamond shaped faces offset
 relative to each other at a rhomboidal angle of
 substantially 20 degrees to make the length of the 55

faces of the cutting bit substantially 2.5 times the perpendicular distance between the rhomboidal end of the bit.

Other objects and a fuller understanding of my invention may be had by referring to the following description and claims, taken in combination with the accompanying drawings, in which like reference characters designate like parts, and in which:

Figure 1 represents a plan view of a mining machine chain lug embodying the features of my invention and is shown in operative relation with a mining machine cutter bar;

Figure 2 represents a top view of a chain lug embodying the features of my invention and having two opposed bit recesses located substantially in the longitudinal center of the chain lug;

Figure 3 is a top view of a chain lug embodying the features of my invention and having two sets of opposed bit recesses, each set being positioned on opposite sides of the longitudinal center of the chain lug;

Figure 4 is a top view of a chain lug embodying the features of my invention and having two opposed bit recesses positioned in the outermost part of the chain lug;

Figure 5 shows the top view of the chain lug shown in Figures 2, 3, and 4 assembled in a chain;

Figure 6 is a front elevational view of the chain lug shown in Figure 3;

Figure 7 is a side elevational view of the chain lug shown in Figures 3 and 6;

Figure 8 is the longitudinal cross-sectional view taken along the line 8—8 of Figure 6;

Figure 9 is a fragmentary and cross-sectional view taken along the line 9—9 of Figure 8;

Figure 10 is a front view of a rhomboidal diamond-shaped cutting bit adapted to fit into the recesses of the chain lug;

Figure 11 is a side elevational view of the rhomboidal diamond-shaped cutting bit shown in Figure 10; and

Figure 12 is a view of a small insert arranged to fit in the unoccupied recess.

In the mining of coal, the coal mining machine is progressively moved along the edge of the vein of coal, as the mining machine cutting chain which is mounted upon the cutter bar cuts a substantially horizontal cleft under the vein of coal. This produced a shelf which is subsequently broken off by means of explosives or other means. In the actual operation, the coal cutting machine may progressively move in one direction along the edge of the coal for a considerable distance, as much as several hundred feet, before the cutting operation is finished. Heretofore, the coal mining machine, which is extremely difficult to move, had to be dragged back to the starting point again, at which place another similar cut was made after the coal previously cut had been removed. As is clearly obvious, the labor and trouble in moving the heavy coal mining machine back to its starting point was rather expensive, as well as entailing a considerable loss of time. However, with the present invention, which embodies a reversible mining machine chain lug, the coal mining machine may cut in the reverse direction, so that it is unnecessary to drag the coal mining machine back to the starting point.

With reference to the drawing, I illustrate three designs of chain lugs in Figures 2, 3, and 4, which are assembled into a mining machine chain that is adapted to move around the cutter bar

10 shown in Figure 1. As illustrated, the cutter bar 10 is arranged to be operated in conjunction with a sprocket wheel 12 that is driven by the mining machine. The cutter bar 10 is provided upon its opposite sides and around its ends with a longitudinal groove 11 into which the lowermost part of the chain lugs slidably move as they are driven by the sprocket wheel 12. The slack in the chain may be adjusted by turning the adjusting screw 13 which varies the position of the cutter bar 10 with respect to the driving sprocket wheel 12. The chain lug may be pivotally connected together by suitable chain straps 17 which have registered openings through which a pivot pin 18 passes pivotally connecting the ends of the straps 17 to the ends of the chain lug. As shown, the chain straps 17 are spaced apart to provide a chain slot to receive the teeth of the driving sprocket wheel 12.

The three designs of the chain lug which are assembled to make up the entire chain and shown in Figures 2, 3, and 4, respectively, are indicated respectively by the reference characters 14, 15, and 16. The chain lug 14 has two opposed bit recesses 23 and 24 for receiving the cutting bit 22. When the cutting chain is arranged to be operated in one direction, the bit 22 is inserted in the bit recess 23, and when the chain is arranged to be operated in the reverse direction, the bit is inserted in the bit recess 24. A set 30 screw 34 is threadably mounted in each end of the chain lug to engage the face of the cutting bit 22 for securely holding it in the bit recesses when the chain is in operation. The bit recesses 23 and 24 are arranged in substantially the longitudinal center of the chain lug 14.

The chain lug 15 has two sets of opposed recesses 25 and 27 and 26 and 28. When the chain is arranged to be operated in one direction, the cutting bits 22 are positioned in the bit recesses 25 and 26 and when the chain is arranged to be operated in the reverse direction, the cutting bits 22 are inserted in the bit recesses 27 and 28. The set of opposed recesses 25 and 27 are positioned closer to the vertical and longitudinal center of the chain lug 15 than the sets of opposed bit recesses 26 and 28.

The chain lug 16 has two opposed recesses 29 and 30 which are respectively adapted to receive the cutting bit 22 for either forward or reverse cutting. As illustrated, the bit recesses 29 and 30 are positioned at the outermost edge of the chain lug 16.

The mining machine chain when assembled is made up of a plurality of sections. As illustrated in Figure 5, each section comprises the three designs of the chain lugs as illustrated in Figures 2, 3 and 4 and the lugs are arranged in four positions and adapted to hold six cutting bits. In other words, in Figure 5, beginning at the left, a section comprises the first four chain lugs. The first chain lug, beginning at the left, has a cutting bit positioned in substantially the longitudinal center of the lug, and being the same as illustrated in Figure 2, the second and third chain lugs being the same as shown in Figure 3, but connected reversely to each other, each with two cutting bits offset at an unequal distance from the longitudinal center of the chain lug and the fourth chain lug being the same as that shown in Figure 4 and having a cutting bit positioned at the outermost edge of the lug. In assembling the entire chain, each section is connected reversely to each other as illustrated in Figure 5. The reversed chain section is not

completely shown in Figure 5, only the two lugs 15 and 16 being shown at the right hand end of the assembly in Figure 5. The two lugs which are not shown on the reverse section would correspond to the two lugs 14 and 15 shown on the left-hand end of the section shown in Figure 5. When the chain in Figure 5 is moved to the left, the cutting action of the first section is from the center to the outside of the chain, and the cutting action of the reversed section is from the outside of the chain to the center of the chain. When the chain is operated in the reversed direction, that is to the right in Figure 5, the bits are removed from their present recesses and inserted into the opposite recesses, in which case the cutting action of the right-hand section is from the center to the outside of the chain, and the cutting action of the left-hand section in Figure 5 is from the outside of the chain to the center of the chain. The entire chain is made up of a plurality of these sections, so that the chains may be operated either in a forward or a reverse cutting direction.

There is another big advantage of having the lugs 15 with two sets of opposed recesses, in that a large number of bits may be used with a less number of lugs. For instance, a single section comprises four lugs, but carries six cutting bits. In other words, for a certain length of chain, there can be many more bits than would be the case when each lug had only one cutting bit. In addition to this advantage, there is another advantage in that the chain may be assembled of three designs of lugs. This clearly reduces the pattern costs and effects a great saving in the manufacturing costs of the chain.

In the construction of the chain lug, it is important that the distance between the cutting point of the cutting bit and a line passing vertically through the chain lug be reduced to a minimum, in order to eliminate as much trouble as possible when the chain lug is passing around the end of the cutter bar as shown upon the right-hand end in Figure 1. In other words, the distance between the two opposed recesses must be as short as possible in order to keep the overall length of the lug as short as possible. Thus, when two opposed recesses are inserted in a lug, it requires more space than if only one recess were inserted in the lug. If the upper body of the chain lug is too long, the rear end of the uppermost part of the lug will strike the coal, as indicated by the broken line 56 in Figure 1 when the chain lug is passing around the right-hand end of the cutter bar. Therefore, in my invention, I provide for sloping the ends upon each side of the central portion of the lug. The sloping ends are indicated by the reference character 35. The main idea is to prevent the ends of the chain lug from swinging around and striking the coal as the chain lug passes around the end of the cutter 10. Also, the shorter the distance between the two ends of the uppermost part of the chain lug, the better the chain lug clears the coal when passing around the end of the cutter bar. Therefore, as shown in Figures 7 and 8, I provide for making the distance 55 as short as possible. To this end, the abutting surfaces 46 and 47 of the recesses 25 and 27 as shown in Figure 8, slope inwardly and downwardly so that the bottom of the two opposed recesses join each other. At the same time, the substantially triangular central lug portion 36 is sufficiently large enough to give strength to the abutting surfaces 46 and 47. This results from the fact that the

cutting bits are rhomboidal in shape in side elevation. The upper rear portion of the two opposed recesses 25 and 27 are provided respectively with sloping engaging surfaces 48 and 49 which engage the heel of the rhomboidal diamond-shaped bit 22. By this construction, the cutting bit 22 is prevented from coming out of the recesses when the set screws 24 are tightly turned in and engaging the forward face of the cutting bit. As illustrated in Figures 7 and 8, the bottom of the bit recesses are provided with opposed surfaces 32 to prevent the bit from tipping forward upon being inserted, which forward position would allow the bit to drop too far into the recesses and not keep the proper gauge, and then if the set screw were tightened against the tipped bit, there would be a fulcrum action and put undue strain upon the bit. The common bottom of the opposed recesses 25 and 27 terminates into a lateral opening 37 which extends from one side of the lug to the other. In this manner, any coal dust or other particles which enter the opposed recesses 25 and 27 is allowed to fall down into the lateral opening and there the dust or other particles may be cleaned out. The description of the opposed recesses 25 and 27 as shown in Figures 7 and 8 applies in the same manner to the other opposed recesses, and the cross-section of the recesses for each of the lugs are substantially diamond-shaped as indicated by the fragmentary view shown in Figure 9.

The shape of the rhomboidal diamond-shaped bit is shown in Figures 10 and 11 and has a forward face 41 and a rearward face 42, which are substantially parallel and offset to each other at a rhomboidal angle of approximately 20 degrees as indicated by the reference character 43. Accordingly, the length of each of the diamond shaped faces from its cutting end to its heel end, that is the end coinciding with the larger angle of the rhomboid, is substantially 2.5 times the perpendicular distance between the two rhomboidal parallel ends 44 and 45. The purpose of this relatively long diamond shaped face is two-fold. First, the upper cutting end of the diamond-shaped face extends sufficiently far above the upper most central portion 36 of the lug to present a good effective cutting tool. Secondly, the lower heel portion of the diamond-shaped face extends far enough into the recesses to present a surface against which the set screw 34 may engage. Otherwise, if the rhomboidal angle 43 was very much more than approximately 20 degrees, the length of the diamond-shaped face of the cutting bit would not be long enough, first, to do effective cutting, and second, to extend sufficiently far into the recesses so that it may be engaged by the set screw 34.

The set screw 34 for the unoccupied recesses may be tightly turned in until the head of the set screw engages the end of the chain lug. This prevents the set screw from becoming loose when in operation. Also, as another means for preventing the set screw 34 of the unoccupied recesses from becoming loose, and maybe eventually lost, while in operation, I provide for inserting a lug 52 into the unoccupied recesses. The lower portion of the lug 52 is substantially diamond-shaped and its upper end has an apron 54 which covers substantially the diamond-shaped opening of the recesses. Above the apron 54, there is a small gripping portion having an opening 53 into which the pointed end of a suitable tool may be inserted for moving the lug from

the recesses. By using the lug 52, the set screws 34 may be tightly turned in against the forward face of the lug 52 to prevent them from becoming loose and eventually lost in some cases.

5 Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

15 1. A reversible mining machine chain lug adapted to hold a rhomboidal shaped bit comprising, in combination, a chain lug having opposed recesses for respectively receiving the bit for forward or reverse cutting, each of said recesses having an abutting surface against which the 20 rear face of the bit abuts, said abutting surfaces sloping downwardly and inwardly to form a common bottom for both recesses and to form a substantially large lug portion between, and to give strength to, the two abutting surfaces with a 25 minimum of longitudinal distance between the cutting point of the bit and a line passing vertically through the center of the lug, and a set screw for each recess to engage the forward face of the bit to hold same therein.

30 2. A reversible mining machine chain lug adapted to hold a rhomboidal shaped bit comprising, in combination, a chain lug having opposed recesses for respectively receiving the bit for forward or reverse cutting, each of said recesses having an abutting surface against which the 35 rear face of the bit abuts, said abutting surfaces sloping downwardly and inwardly to form a common bottom for both recesses and to form a substantially large lug portion between, and to give strength to, the two abutting surfaces with a 40 minimum of longitudinal distance between the cutting point of the bit and a line passing vertically through the center of the lug, a set screw for each recess to engage the forward face of the 45 bit to hold same therein, the central lug portion between the opposed recesses constituting the uppermost part of the lug, and the end portion upon each side of the recesses sloping downwardly from the central lug portion to reduce the 50 radial distance between the pivotal turning point of the lug and each of the upper end corners of the lug.

3. A reversible mining machine chain lug adapted to hold a rhomboidal shaped bit comprising, in combination, a chain lug having opposed recesses for respectively receiving the bit for forward or reverse cutting, each of said recesses having an abutting surface against which the rear face of the bit abuts, said abutting surfaces 55 sloping downwardly and inwardly to form a common bottom for both recesses and to form a substantially large lug portion between, and to give strength to, the two abutting surfaces with a minimum of longitudinal distance 60 between the cutting point of the bit and a line passing vertically through the center of the lug, and a set screw for each recess to engage the forward face of the bit to hold same therein, each of the recesses having an upper and rear- 65 ward engaging bit surface disposed at an outward angle to the abutting surface to hold the bit in the recess.

4. A reversible mining machine chain lug adapted to hold a rhomboidal shaped bit comprising, in combination, a chain lug having op-

posed recesses for respectively receiving the bit for forward or reverse cutting, each of said recesses having an abutting surface against which the rear face of the bit abuts, said abutting surfaces sloping downwardly and inwardly to form a common bottom for both recesses and to form a substantially large lug portion between, and to give strength to, the two abutting surfaces with a minimum of longitudinal distance between the cutting point of the bit and a line passing vertically through the center of the lug, a set screw for each recess to engage the forward face of the bit to hold same therein, each of the recesses having an upper and rearward engaging bit surface disposed at an outward angle to the 15 abutting surface to hold the bit in the recess, the central lug portion between the opposed recesses constituting the uppermost part of the lug, and the end portion upon each side of the recesses sloping downwardly from the central lug portion to reduce the radial distance between the pivotal turning point of the lug and each of the upper end corners of the lug, the bottom of said bit recesses having at their bottoms opposed surfaces to prevent the bit from tipping forward 20 upon being inserted in the said bit recesses and to maintain the proper gauge.

5. A double and reversible mining machine chain lug adapted to hold rhomboidal shaped bits comprising, in combination, a chain lug having two sets of opposed recesses for respectively receiving a set of bits for forward and reverse cutting, each of said recesses having an abutting surface against which the rear face of the bits abuts, the said abutting surfaces of each set of 30 opposed recesses sloping downwardly and inwardly to form a common bottom for the recesses of each set and to form a substantially large lug portion between, and to give strength to, the abutting surfaces of each set of recesses 35 with a minimum of longitudinal distance between the cutting points of the bits and a line passing vertically through the center of the lug, one of said sets of opposed recesses being positioned upon one side of the longitudinal and vertical center of the chain lug and the said other set of opposed recesses being positioned upon the other side of the said longitudinal and vertical center of the chain lug, and a set screw for 40 each recess to engage the forward face of the bit 45 to hold the same therein.

6. A double and reversible mining machine chain lug adapted to hold rhomboidal shaped bits comprising, in combination, a chain lug having two sets of opposed recesses for respectively receiving a set of bits for forward and reverse cutting, each of said recesses having an abutting surface against which the rear face of the bits abuts, the said abutting surfaces of each set of opposed recesses sloping downwardly and 55 inwardly to form a common bottom for the recesses of each set and to form a substantially large lug portion between, and to give strength to, the abutting surfaces of each set of recesses with a minimum of longitudinal distance between 60 the cutting points of the bits and a line passing vertically through the center of the lug, one of said sets of opposed recesses being positioned upon one side of the longitudinal and vertical center of the chain lug and the said other set of 65 opposed recesses being positioned upon the other side of the said longitudinal and vertical center of the chain lug, and a set screw for each recess to engage the forward face of the bit to hold the same therein, one of said sets of opposed recesses 70

being positioned farther from the said longitudinal and vertical center of the chain lug than the other said set of opposed recesses.

7. A reversible mining machine chain lug adapted to hold a rhomboidal shaped bit comprising, in combination, a chain lug having opposed recesses for respectively receiving the bit for forward or reverse cutting, each of said recesses having an abutting surface against which the rear face of the bit abuts, said abutting surfaces sloping downwardly and inwardly to form a substantially large lug portion between, and to give strength to, the two abutting surfaces with a minimum of longitudinal distance between the cutting point of the bit and a line passing vertically through the center of the lug, and a set screw for each recess to engage the forward face of the bit to hold same therein.

8. A reversible mining machine chain lug adapted to hold a rhomboidal shaped bit comprising, in combination, a chain lug body having opposed recesses for respectively receiving the bit for forward or reverse cutting, each of said recesses having an abutting surface against which the rear face of the bit abuts, said abutting surfaces sloping downwardly and inwardly to form a substantially large lug portion between, and to give strength to, the two abutting surfaces with a minimum of longitudinal distance between the cutting point of the bit and a line passing vertically through the center of the lug, the portion of the body in rear of the recesses being elevated above the portions of the body in advance of the recesses, the body portion in rear of the recesses constituting a good strong support for the bit, the body portions in advance of the recesses being relatively low to clear the surface being cut and having a set screw threadably mounted therein with the end of the set screw entering the recesses at a considerable distance below the uppermost part of the said body portion which is in rear of the recesses, each of the said recesses having an abutting surface sloping downwardly against which the rear portion of the bit engages, the uppermost portion of abutting surface extending forwardly at an angle substantially parallel to the rhomboidal angle of the bit to prevent the bit from coming out of the recesses.

9. The combination, with a reversible-double ended rhomboidal bit in side elevation and having forward and rearward diamond shaped faces substantially parallel and offset relative to each other at a rhomboidal angle of approximately 20 degrees to make the length of the said cutting faces substantially 2.5 times the perpendicular distance between the rhomboidal ends of the bit, and having a rearward pair of lateral surfaces which diverge downwardly from the top edge, and a forward pair of lateral surfaces which diverge upwardly from the bottom edge and join the rearward pair of downwardly diverging lateral surfaces on substantially the rhomboidal centerline of the bit, of a body portion having a recess for receiving said bit, said recess being open at its top and having deep lateral sides for engaging a substantial part of the bit, the inner

surfaces of said recess having a plurality of engaging portions for engaging the bit, one of said engaging portions comprising two spaced upwardly diverging surfaces for engaging the forward pair of upwardly diverging surfaces of the bit, another of said engaging portions comprising a flat rearward surface extending downwardly from a point near the top of the body portion for engaging the flat rearward face of the bit, another of said engaging portions comprising a pair of spaced downwardly diverging surfaces to engage the rearward pair of downwardly diverging surfaces of the bit, another of said engaging portions comprising a sloping engaging portion which extends angularly out from the flat rearward engaging portion to engage the top edge of the bit, the said engaging portions being so arranged that the bit can only enter or leave the open top at substantially the rhomboidal angle, and clamping means to engage the forward face of the bit for holding the bit against movement at the rhomboidal angle, the cutting face of the bit presenting a good effective cutting portion above the said body portion and presenting a lower heel portion far enough into the recess against which the clamping means may engage.

10. The combination, with a reversible-double ended rhomboidal bit in side elevation and having forward and rearward diamond shaped faces substantially parallel and offset relative to each other at a rhomboid angle of approximately 20 degrees to make the length of the said cutting faces substantially 2.5 times the perpendicular distance between the rhomboidal ends of the bit, and having a rearward pair of lateral surfaces which diverge downwardly from the top edge, and a forward pair of lateral surfaces which diverge upwardly from the bottom edge and join the rearward pair of downwardly diverging lateral surfaces on substantially the rhomboidal centerline of the bit, of a body portion having a recess for receiving said bit, said recess being open at its top and having deep lateral sides for engaging a substantial part of the bit, the inner surfaces of said recess having a plurality of engaging portions for engaging the bit, one of said engaging portions comprising two spaced upwardly diverging surfaces for engaging the forward pair of upwardly diverging surfaces of the bit, another of said engaging portions comprising a flat rearward surface for engaging the flat rearward face of the bit, another of said engaging portions comprising a pair of spaced downwardly diverging surfaces to engage the rearward pair of downwardly diverging surfaces of the bit, the said engaging portions being so arranged that the bit can only enter or leave the open top at substantially the rhomboidal angle, and clamping means to engage the forward face of the bit for holding the bit against movement at the rhomboidal angle, the cutting face of the bit presenting a good effective cutting portion above the said body portion and presenting a lower heel portion far enough into the recess against which the clamping means may engage.

CHARLES L. BOWMAN.
